UNITED STATES PATENT OFFICE.

ADELBERT E. BRONSON, JR., OF CLEVELAND, OHIO.

SAD-IRON.

1,123,840.

Specification of Letters Patent.

Patented Jan. 5, 1915.

Application filed December 12, 1910. Serial No. 596,757.

To all whom it may concern:

Be it known that I, ADELBERT E. BRONSON, Jr., a citizen of the United States, residing at Cleveland, in the county of Cuyahoga and 5 State of Ohio, have invented a certain new and useful Improvement in Sad-Irons, of which the following is a full, clear, and exact description.

This invention is an improvement in the 10 kind of sad irons which have a removable heating core,—the object being to provide a sad iron of this sort, so constructed that the operator may, with the handle part of the device, lift the core from the protecting bot- 15 tom plate and put it on the stove, and then disconnect the handle from the core, leaving the core to be heated, and may then, with the handle, pick up this core, and, if desired, place it again on the bottom plate and connect all three parts together in operative re- 20 lation.

The sad iron embodying the invention comprises three principal members, to wit, 25 a handle member, a protecting bottom plate, and a heating core; and the handle member carries connecting devices by means of which it may be connected with or disconnected from the core, or all three parts connected together, as circumstances require; and the invention consists in the combination 30 of these parts as defined by the appended claims.

In the drawing, Figure 1 is a central sectional view of the sad iron embodying the 35 invention. Fig. 2 is a bottom plan view of the handle member. Fig. 3 is a side elevation, partly sectioned, of the device when the handle member is connected with the core only.

In the drawing A represents the core which is, or may be, a block of cast iron of the required shape; and the lower surface of this block may be smoothly finished so as to make it capable of use for ironing purposes. In fact when one is practically using 45 one of the described irons, the rough work will generally be done with this uncovered block.

B represents the protecting bottom plate, 50 the lower surface of which is highly finished and is intended to be used generally for producing the ironing or smoothing effect for which the device is provided, especially on fine goods. This bottom plate has preferably an upturned marginal flange b.

D represents the handle member, which consists essentially of a top plate d and handle d' which is fixed thereto. This plate has, preferably, a down-turned marginal flange d², and is of such shape that this 60 marginal flange may embrace the core somewhat loosely. Preferably also a thin casing G is fitted over this flanged plate, said casing having a flange g which fits around the flange d². There two flanged plates imprison between them and their flanges a thin 65 layer of air which serves as a heat insulator to minimize the loss of heat in the core block, and to prevent the upper plate and handle from getting uncomfortably hot. 70 The feet d⁴ of the handle proper rest upon the plate portion of the casing G, and are secured in place by bolts J.

At about the middle of the plate d is a circular depression d⁵, within which a rocker F is mounted on a vertical axis. As a matter of fact, this rocker is fixed to a shaft f which has its bearings in a downwardly extended boss d⁶ and in a hole through the 75 plate member of the casing G. A handle H is fixed to the upper end of this shaft.

Two bolts E, E are connected by vertical pivots with this rocker on opposite sides of its center; and these bolts extend in opposite directions from the rocker toward the ends 80 of the handle member. Near their ends the bolts are turned down, and the down turned portions e pass through slots d⁷ in the plate d. The extreme ends e' of these bolts are 85 pointing toward the ends of the core. The core has near its ends vertical slots a of such width as to permit the ends e' of the bolts to enter them. Near the bottom of these slots holes a' are formed through the 90 ends of the core. By turning the handle H of the rocker the bolts may be thrust outward so that their ends will enter these holes. This being done, the handle member and the core will become attached, as shown in 95 Fig. 3. The core may be lifted by the handle member and placed upon the bottom plate B. Then, by turning the handle H still further, the bolts will be moved so that 100 their ends will project through the holes a' in the core and beneath shoulders b' formed at the ends of the bottom plate. These shoulders are, in the construction shown, formed by little shelves secured horizontally 105 across the points of the flange b of the bot-

110

tom plate, and in a plane just above the plane of the tops of the bolts.

In order to facilitate the back and forth movement of the bolts E, E, depressions d^s 5 are formed in the top surface of the plate D, and rollers K are placed in these depressions below the bolts E, so that said bolts rest and ride upon them.

Having described my invention, I claim:

- 10 1. In a sad iron, the combination of a handle member which includes a top plate, an attached handle and a casing over the top plate, said casing having a down-turned marginal flange, a rocker lying between the 15 said top plate and casing and pivoted to both on a vertical axis, two locking bolts pivotedly connected to said rocker on opposite sides of the pivot and having their ends turned downward and then outward 20 into horizontal position, a core having openings therein in which the horizontal portion of the bolts may coöperate, and a bottom plate having shoulders with which the bolts may also coöperate.
- 25 2. In a sad iron, the combination of a handle member comprising essentially a plate and an attached handle, a rocker mounted on said handle member, and two bolts mounted on the handle member and 30 connected with said rocker, with a core having horizontal holes into and through which the ends of said bolts may be moved by said rocker, and a bottom plate having shoulders under which the bolt ends may 35 engage when they are moved through the holes in said core.
3. In a sad iron, the combination of a bottom plate having an upturned marginal flange, a handle member comprising a 40 handle and an attached plate having a down turned marginal flange which fits within the flange of the bottom plate, a core adapted to be inclosed by said flanged top and bottom plate, locking bolts mounted upon

the handle member plate, a rocker mounted 45 on the latter plate for operating said bolts, the core having holes through which the bolts may pass, and the bottom plate having shoulders under which said bolts may 50 pass when they have been thrown to the limit of their outward movement, and an operating handle fixed to said rocker.

4. In a sad iron, the combination of a handle member which includes a top plate, an attached handle, and a casing over the 55 top plate, said casing having a down turned marginal flange, a rocker lying between the said top plate and casing and pivoted to both on a vertical axis, two locking bolts pivotedly connected with said rocker on opposite sides of its pivot, and having their ends turned downward and then outward into horizontal position, a core having vertical slots near its ends and horizontal holes near the bottom of said slots, and bottom 60 plate having shoulders which lie in a plane just over the tops of said holes.

5. In a sad iron, the combination of a handle member which includes a top plate and an attached handle, said plate having 70 in its top surface two depressions, a roller mounted in each depression, a rocker mounted on said handle member, and two bolts connected with the rocker, which bolts extend in opposite directions therefrom and 75 pass over and rest upon said rollers, with a core having horizontal holes into and through which the ends of said bolts may be moved by said rocker, and a bottom plate having shoulders under which the bolt ends 80 may engage when they are moved through holes in said core.

In testimony whereof, I hereunto affix my signature in the presence of two witnesses.

ADELBERT E. BRONSON, JR.
